UNITED STATES PATENT OFFICE.

FRANK MOSSBERG, OF ATTLEBORO, MASSACHUSETTS.

REEL.

No. 851,867.

Specification of Letters Patent.

Patented April 23, 1907.

Application filed November 1, 1906. Serial No. 341,579.

To all whom it may concern:

Be it known that I, FRANK MOSSBERG, a citizen of the United States, residing at Attleboro, in the county of Bristol and State of Massachusetts, have invented certain new and useful Improvements in Reels, of which the following is a specification.

My invention relates to spools or reels of large size, such as are used for carrying wire, 10 lead-covered telephone cables and the like, and which consequently, require to be very strongly and solidly constructed, in order to support the heavy loads and withstand the rough usage to which they are subjected.

15 Heretofore, reels for the described, and other similar purposes, have been constructed so far as I am aware, either wholly of wood, or partly of wood and partly of cast iron. Such reels are necessarily very heavy 20 and consequently clumsy, and do not prove satisfactory in practice.

The object of my invention is to improve the construction of reels of the class described by making the heads, which are necessarily 25 of large diameter and must be capable of supporting a great weight, out of sheet-metal, which is pressed into shape to admit of ready and secure attachment of the hub to the heads, and to impart great rigidity and stiffness 30 to the latter as well as to the whole structure. The heads are also provided with means whereby the reel may be mounted on bearings, so that it can be rotated, as for instance, while the wire or cable is being wound 35 onto, or unwound from the reel.

The construction of my improved reel will now be described in detail, reference being had to the accompanying drawings, in which,

Figure 1 is an end elevation of a reel embodying my invention; Fig. 2 is a central longitudinal section thereof; Fig. 3 is an end view of a modified construction, and Fig. 4 is a central longitudinal section thereof.

45 My improved reel consists primarily in a hollow cylindrical hub 1, made of sheet metal, preferably steel, the same being formed by bending a plate of suitable size into cylindrical form, the longitudinal seam between the opposed edges of the same being preferably secured by a butt-riveted joint, shown in Fig. 2, the same comprising a longitudinal strip 2, secured to both edges of the seam by rivets 4. The joint may be welded, if preferred.

55 The other component parts of my improved reel are the heads 5, 5, which are

made from steel-plates pressed into the desired shape in dies; the axial sleeve or tube 6, which is secured at its ends to the heads and which forms the journal by which the reel 60 may be pivotally mounted, and the bolts 7 which secure the component parts of the structure together.

The heads are made, as I have stated, of steel-plate, a disk of the desired diameter being first cut out and then placed in dies in which it is pressed, in the usual way, into the shape shown. When completed, it has a central circular boss 8, in the center of which is formed a circular aperture for the reception 70 of the end of the sleeve 6, the edge of said aperture being preferably offset, as shown at 9. The walls of said central bosses are curved around into the plane of the disk, as indicated at 10. Circularly arranged projections 75 or shoulders 12, of larger diameter than the bosses 8, are formed on the opposite sides of the disks from said bosses, said shoulders or projections serving to internally support the ends of the hubs in the completed reel. 80

The edges or peripheries of the disks may be left flat, but I prefer to turn the same over to form a flange 13, which serves to strengthen the reel as well as to form a bearing surface for the same when it is not pivotally supported.

At the same time as the disks are pressed into the shape just described a number of radial ribs 14 are, or may be, formed therein, the function of which is to impart greater 90 rigidity and stiffness to the head.

Near each end of the sleeve 6 is formed a shoulder 16 against which the inner edges of the central apertures in the heads bear, and the ends of the sleeve can then be riveted 95 over to permanently and securely attach said sleeve to the heads, as shown in Fig. 2.

In order to secure the hub 1 in place between the heads, on the shoulders or projections 12 of which the ends of said hub rest, 100 the bolts 7 are passed through suitable holes formed in the heads within the said circular projections or shoulders, when the nuts 17 on said bolts are tightened the whole structure is rigidly secured together. 105

The modification in the structure of my improved reel, shown in Figs. 3 and 4, resides in this, that, instead of the continuous circular shoulder or projection 12, a number of separate projections or shoulders 18 are 110 formed by punching the metal of the head inwardly at a number of equidistant points.

in a circle of the desired diameter. The manner in which this is done will be obvious to persons familiar with the art of metal-working from an inspection of the drawing. In this form of my invention I have shown an additional sleeve 19 surrounding the central sleeve or journal 6, the ends of said sleeve 19 bearing against the inner surfaces of the offset portions 9 of said heads ¹⁰ rounding the central apertures. This sleeve 19 takes the place of the shoulders 16 of the sleeve 6, described in the form of my invention shown in Figs. 1 and 2. In other respects the construction of the two forms of reel is the same.

In assembling the parts, the hub 1 is placed over the sleeve 6, or sleeves 6 and 19, and the heads 5 are slipped over the ends of sleeve 6, with their shoulders or projections fitting ²⁰ within the ends of the hub, the bolts are then put in place and finally the ends of the sleeve 6 are flanged or riveted over.

Having thus described my invention and without wishing to be limited to the exact ²⁵ form and details of construction shown, what I claim is—

1. A reel of the class described, the same consisting of a hollow, cylindrical sheet-metal hub, pressed steel heads each having a ³⁰ series of circularly arranged integral shoulders or projections fitting within the ends of said hub to support the same concentrically, said heads also having central circular apertures, a tubular journal passed through said

apertures and secured to the edges thereof at ³⁵ its ends and a circular series of bolts joining said heads together within said hub.

2. A reel of the class described, the same consisting of a hollow, cylindrical sheet-metal hub, heads for said reel, each comprising ⁴⁰ a metal disk pressed in dies to form therein a central circular boss provided with a central aperture, the edges of which are offset, and a circular shoulder on the opposite side from said boss and of larger diameter ⁴⁵ than the latter, the ends of said hub fitting onto said circular shoulders, and a journal or sleeve having its ends flanged over said offset edges of the apertures in said heads.

3. A reel of the class described, the same ⁵⁰ consisting of a hollow, cylindrical sheet-metal hub, pressed steel heads secured to the ends of said hub and each having an integral internal shoulder or projections fitting within said hub, a central journal or sleeve passing ⁵⁵ through said heads and provided with shoulders to bear against the inside faces of said heads, the ends of said sleeve being flanged or riveted over externally of said heads to secure the same thereto.

In testimony whereof I have signed my name to this specification in the presence of two subscribing witnesses.

FRANK MOSSBERG.
